UNITED STATES PATENT OFFICE.

EDWARD MILTON WILDEY, OF CANONBURY, LONDON, ENGLAND.

DEVICE FOR CUTTING SCREW-THREADS BY CHASERS.

1,313,568.

Specification of Letters Patent.

Patented Aug. 19, 1919.

Application filed February 1, 1918. Serial No. 215,012.

To all whom it may concern:

Be it known that I, EDWARD MILTON WILDEY, a subject of His Majesty King George V of the United Kingdom of Great Britain and Ireland and of the British Dominions beyond the Sea and Emperor of India, residing at Canonbury, London, England, have invented certain new and useful Improvements in Devices for Cutting Screw-Threads by Chasers, of which the following is a specification.

The present invention relates to improvements in chaser holding or serving devices as described in the specification of my United States application No. 203,286 dated 21st November, 1917. In that specification No. 203,286 there is described a duplex or balanced supporting control device for chasers *a*—*b* comprising two chaser holders, each on a rocking upright *e*, *e'*, with eccentric *g*, *g'* for the adjustment of height, the uprights being made to approach or recede by a lever hinged to a support, for example, a crane arm *k* rising from the base plate clear of the work, the intermediate mechanism consisting of links *m*, *m'* which are drawn or pushed by a double eccentric system attached to the axis *l* and shown at *n*, *n'*, and a locking pawl operating into a toothed arc piece *p*.

The improvement according to the present invention consists in embodying such mechanism as shall enable the chasers to cut so as to finish the screw close to a face, then automatically to recede the chasers out of cutting range when the face is reached, and also allow the lathe saddle, (to which the device is fixed) to move forward some distance while the chasers remain against the face but recede from the cutting range of the work.

Figures 1, 2 and 3 represent the present improvement, Fig. 1 being a front view; that elevation of the device which approaches or recedes from the nose of the lathe mandrel being regarded as the front. Fig. 2 is a sectional view, at A, A, of Fig. 1. Fig. 3 is a back view, or as seen from the puppet end of the lathe bed.

In the drawings like references are used to indicate like parts of the device illustrated in the aforesaid prior specification No. 203,286.

In carrying out the present improvement the base plate *c* of the chaser holder or server described in my previous specification is

made double, *c'* and *c''*, and with suitably formed grooves or V's so that the portion *c''* may slide parallel to the axis of the lathe independently of the portion *c'* which is attached to the saddle of the lathe.

The crane arm *k* (or as depicted a double arm *k*, *k'* with a common end) carries in its lower portion a horizontal sliding bolt *q*. That end of the bolt *q* which is nearest the face at which the thread finishes is fitted with an adjustable feeler *r* on which is mounted an eccentric collar or rim *r'*, while the other end of the bolt keys into a spring-actuated vertical sliding bolt or bolt-system *s* which has its bearings in one of the lugs *d* of the chaser holder base. The keying at the end of the horizontal bolt *q* working in the vertical bolt *s* is shaped so as to allow the vertical bolt or bolt-system to rise by tension of the spring *s'* when the horizontal bolt *q* is moved backward against the tension of it spring *q'*. The lower end of the vertical bolt or bolt system *s* may be tapered so to more readily enter a correspondingly tapered recess in the auxiliary base *c'* thus locking together the two base elements *c'* and *c''*. Immediately over the top of the vertical bolt or bolt system, and in contact therewith, is a curved lever *t'*, *t''*, *t'''*. This lever is fulcrumed in the crane arm about midway of its curve at *t''*. The upper end of the lever is formed as a pawl which engages a ratchet *p* formed on the boss of the arm *i*. The boss is surrounded by a coiled spring *i* one end of which is fastened to the crane arm or double arm *k*, *k'* and the other end of which is fastened to the arm *i*. A spring may be placed between a projection *u* on the under side of the chaser holder base *c''* and the side *v'* of an elongated recess *v*, in the auxiliary base *c'*. But ordinarily any such intervening spring may be dispensed with and, as shown, contact of the projection *u* with the side *v'* of the recess *v* is arranged to register the bases for locking together by the bolt system *s*. A horizontal lever *w* passes through a slot in the chaser holder base, and has one of its ends pivoted on the auxiliary base; the other end of the horizontal lever conveniently has a handle for operating. During cutting operations, the two bases are locked together by the lower end of the vertical bolt or bolt system *s*.

The vertical bolt or bolt system *s* which is illustrated consists of a hollow bolt *s''* adapted at the lower and open end to engage a

socket s^3 in the slide guide or auxiliary base c' and having at the upper and perforated end a saddle-like piece s^4 into which the corresponding and flat end of the bolt q enters for locking and releasing a bolt s^5 which is 5 slidably mounted in the perforated upper end of the bolt s^2 and the top of the saddle piece s^4 and adapted to be held retracted by the flat end q^2 of the bolt q engaging in the recessed end of the bolt s^5 .

10 When the bolt q is moved backward, a notch q^3 frees the bolt s^5 for rise by the pressure of the spring s' interposed between a collar on the shank of the bolt s^5 and a transverse pin s^6 which runs through slots in the two bolts, the arrangement being such that first the lever t' is raised by rise of the bolt s^5 to withdraw the pawl t^3 and release the ratchet p which holds the chasers to duty, 15 and when the back pressure which tends to bind the bolt s^2 having been thus relieved, the further upward movement of the bolt s^5 in contacting through the intermediary of its shoulder with the perforated end of the bolt s^2 raises the bolt s^2 clear of its socket s^3 .

20 25 The operation of the improved device is as follows:—

The auxiliary base is fastened to the saddle of the lathe, and the two bases are locked together by the lower end of the vertical bolt or bolt system s . The eccentric rim on the feeler head of the horizontal bolt q is so adjusted by rotation that when the chasers have arrived at the face, the horizontal bolt 30 has moved backward to its full limit and its 35 appropriately shaped end which keys into the vertical bolt or bolt system s is then in such a position that the vertical bolt is freed for vertical movement, and is forced upward by its spring. In the same upward 40 movement the end of the bolt or bolt system s is withdrawn from the auxiliary base immediately the upper end of the vertical bolt or bolt system s has moved the curved lever t' , t^2 , t^3 to withdraw its pawl end out of engagement with the ratchet; and so release the ratchet for backward movement under the impulse of its coiled spring i' . The chasers are thus receded from the work and 45 as the bases are free to move relatively, the motion of the lathe saddle may continue while the lathe is being reversed or stopped. Before commencing operations again the two bases are brought into locking position 50 by the horizontal lever provided and locked by the vertical bolt being pressed down by the curved lever. When the curved lever is 55 pressed down and in locking position the horizontal sliding bolt q moves forward under the pressure of the spring q' and locks the vertical bolt in retracted position.

60 65 What I claim is:—

1. In a device of the class described the combination of a lathe saddle, a supporting control device or server for chasers, a slide

guide connection of the device or server to the saddle, mechanism for locking said device to the lathe saddle, mechanism for holding the chasers to duty, and releasing mechanism for said locking and holding mechanism, said releasing mechanism operatively co-acting with a face or flange of the work, substantially as described. 70

2. In a device of the class described the combination of a lathe saddle, a supporting control device or server for chasers, a slide guide connection of the device or server to the saddle, locking mechanism for locking the device or server to the lathe saddle, said locking mechanism comprising a vertical bolt system, and a horizontal retaining bolt therefor, a feeler operatively contacting with the face or flange of the work for releasing said retaining bolt and locking mechanism for the chasers controlled by said bolt system, substantially as described. 75 80 85

3. In a device of the class described the combination of a lathe saddle, a supporting control device or server for chasers, a slide guide connection of the device or server to the saddle, locking mechanism for locking the device or server to the lathe saddle, said locking mechanism comprising a vertical bolt system, and a horizontal retaining bolt therefor, an adjustable feeler operatively contacting with the face or flange of the work for releasing said retaining bolt and locking mechanism for the chasers controlled by said bolt system, substantially as described. 90 95 100

4. In a device of the class described the combination of a lathe saddle, a supporting control device or server for chasers, a slide guide connection of the device or server to the saddle, locking mechanism for locking the device or server to the lathe saddle, said locking mechanism comprising a vertical bolt system, an actuating spring therefor, a horizontal retaining bolt engaging said vertical bolt system, an adjustable feeler operatively contacting with the face or flange of the work for releasing said retaining bolt, and locking mechanism for the chasers controlled by said bolt system, substantially as described. 105 110 115

5. In a device of the class described the combination of a lathe saddle, a supporting control device or server for chasers, a slide guide connection of the device or server to the saddle, locking mechanism for locking the device or server to the lathe saddle, said locking mechanism comprising a vertical bolt system, an actuating spring therefor, a horizontal retaining bolt engaging said vertical bolt system, an adjustable feeler operatively contacting with the face or flange of the work for releasing said retaining bolt, and locking mechanism for the chasers comprising a spring controlled ratchet, a locking pawl, and a releasing lever therefor, said 120 125 130

lever being controlled by the bolt system, substantially as described.

6. In a device of the class described the combination of a lathe saddle, a supporting control device or server for chasers, a slide guide connection of the device or server to the saddle, mechanism for locking said device to the lathe saddle, mechanism for holding the chasers to duty, releasing mechanism

for said locking and holding mechanism, 10 said releasing mechanism operatively co-acting with a face or flange of the work, and means for restoring the parts to operative position after release, substantially as described.

15

In testimony whereof I affix my signature.

EDWARD MILTON WILDEY.
